DEFENSIVE PUBLICATION

UNITED STATES PATENT OFFICE

Published at the request of the applicant or owner in accordance with the Notice of Dec. 16, 1969, 869 O.G. 687. The abstracts of Defensive Publication applications are identified by distinctly numbered series and are arranged chronologically. The heading of each abstract indicates the number of pages of specification, including claims and sheets of drawings contained in the application as originally filed. The files of these applications are available to the public for inspection and reproduction may be purchased for 30 cents a sheet.

Defensive Publication applications have not been examined as to the merits of alleged invention. The Patent Office makes no assertion as to the novelty of the disclosed subject matter.

8 Sheets Drawing, 21 Pages Specification

An output display terminal which includes an addressable message buffer for storing characters to be displayed on the screen of the terminal. The terminal responds to a data stream which includes a repeat to address [RTA] buffer control order, a stop address [A1, A2] and a specified alphabetic or null character. In executing the order, the specified character is stored in all buffer locations starting at the current buffer address and ending at but not including the specified stop address. With this single order, a specified character may be displayed in successive display positions or a succession of nulls, blanks or spaces may be inserted following the last significant character of a display field.
